CLAIM

The ornamental design for a decal for an automobile, as shown and described.

DESCRIPTION

FIG. 1 is a plan view of a decal for an automobile showing a first embodiment of my design against a black background; and,

FIG. 2 is a plan view of a decal for an automobile showing a second embodiment thereof.

In the drawings, the colors red and black are part of the claimed design.

The broken lines in the drawings is a boundary and forms no part of the claimed design.
